UNITED STATES PATENT OFFICE.

PATRICK HARVEY, OF CHICAGO, ILLINOIS.

WATER-PRESSURE REGULATOR.

SPECIFICATION forming part of Letters Patent No. 257,697, dated May 9, 1882.

Application filed April 4, 1881. (No model.)

To all whom it may concern:

Be it known that I, PATRICK HARVEY, of Chicago, in the county of Cook and State of Illinois, have invented a new and useful Water-
5 Pressure Regulator; and I hereby declare the following to be a full, clear, and exact description of the invention, which will enable others skilled in the art to which it appertains to make and use the same, reference being had to the accompanying drawings, forming a part here-
10 of, and in which—

Figure 1 represents a longitudinal and vertical central section of my improved hydraulic apparatus with the pistons and moving parts connected therewith at their lower end of travel and the water-ways open. Fig. 2 represents the same with the pistons and moving parts connected therewith near the upper end of their stroke and the water-ways closed; and Fig. 3
15 represents an arrangement of a lever connected by a wire to the lever working the pistons, for the purpose of operating the same for special purposes hereinafter mentioned.

Like letters of reference indicate like parts.
25 The object of my invention is to supply a combined pressure-regulator, relief, stop, and waste valve, the several parts of which are constructed, combined, and operated substantially as hereinafter described and shown.

30 In the drawings, A represents a cylindrical shell, provided with an inlet-pipe, e, connecting with the water-main, and an exit or house-supply pipe, f, and a waste or relief pipe, g.

Within the interior of the shell A, and immediately above the inlet e and below the pipe f, is fastened an annular ring, h², which forms a diaphragm, to which a short tube or cylinder, h', is attached, so as to project about equal distances above and below said diaphragm.

40 To the lower end of the shell A is attached a cap, c, to which is attached a cylinder, b, the upper end of which reaches to, or nearly to, the opening e, and which is made of the same internal diameter as the tube h'. A packing, a, is shown between the cap c and end of the shell A.

Upon the upper end of the cylinder A is secured a cap, o, pressing upon a leather washer, o', and which rests upon a metal washer, o²,
45 and thereby forms a tight joint between the

shell A and its cap o, and also between that of the cap o and rod p.

Concentrically within the shell A is a tube, i', to which are attached fixed flanges m and m², against which are placed self-packing leather washers n and l, forming water-tight pistons within the sides of the cylinders A and h'. The packing n is held upon the flange m by the flanged nut m', and the packing l by one of the flanges k of the shell or sleeve j slipped over the tube i'.

Against the lower flange k of the tube j is placed a self-packing washer, forming the piston l' within the cylinder b, and which is held in place by the flanged nut i on the lower end 65 of the tube i'.

The tube i' is pierced with several holes, i², between the flanges m and m², and may be made solid above said holes.

Beyond the nut m' the stem i' is provided with a thread, r, screwed into the rod p. The part extending beyond the cap o is provided with a slot, q, through which passes a lever, D, fulcrumed in the post C, said post C being attached to a bracket, B, on the shell A.

The lever D is provided with an adjustable weight, s, and at its end is connected a wire, t, the other end of which is connected to a bell crank lever, u, by means of which the lever D may be raised and held by catching the lever u in a notch or catch, v, in the upper part of the annular disk v'.

The parts s, u, v, and v' are shown on a reduced scale. All the other parts are shown full size, and the rod above the cap o is not 85 shown in section.

The lever u may be located in any part of the house and connected by means of bell-cranks and wires to the lever D, which, with all the other parts of the apparatus, should be 90 located in the basement, so that it, with its pipes, may be beyond the reach of frost, and so that the waste-pipe g may be readily connected with a sewer-pipe.

The manner of operating my improved hydraulic apparatus is as follows, to wit: To obtain a water-supply the lever D, by means of the lever u, is placed as shown in Fig. 1. The weight s being heavy enough to pull it down, water will then pass through e, h', and f, and 95 tco

will be prevented from passing out through g by means of the piston n . Water also passes through the holes i^2 and stem i' into the chamber h , where it gives an upward pressure proportionate to its head, which is balanced, or nearly so, by the exterior downward pressure on the piston l' , but is in excess upward in proportion as the areas of the pistons l' and n are to each other, and which would cause the pistons to rise if not counteracted by the lever D and its adjusted weight s . The weight s may be so regulated that so long as the water is being drawn from f the pistons will remain in their lower position; but as soon as the flow is stopped the pressure against the pistons n and l' will cause them to rise, and thus draw the piston l into the cylinder h' , where it is held, and the water-ways thereby closed until water is again drawn from f , thus forming an automatic pressure-regulator adapted to operate to any pressure that the weight s may be desired to give on the house side, while the pressure on the main may vary indefinitely. When the piston l is closed and the water in the house-boiler is heated its expansion causes an increased or dangerous pressure upon the pipe f , which in this case acts against the under side of the pistons l' and n , thus raising them with their adjusted weight still higher, as shown by the dotted outline of the lever D , until the piston n relieves the same through the waste-pipe g into the sewer. When it is desired to drain the pipe f , either to prevent its freezing or for repairs, the lever u is turned so as to catch in the notch v , and thereby raise the lever D beyond the position as now shown in Fig. 2, but indicated by the dotted outline thereof, and thereby cause the piston n to rise still higher and open the passage through the pipe g , the lever u being so constructed as to cause the pistons to rise to the desired place, where they are permanently held until the lever u is again released from the notch v into the position as now shown.

It will be observed that the pistons l and l' are balanced against each other when the piston or valve l is within its cylinder h' , and that the upward pressure on the valve n is equal to that of the area of the chamber h plus the excess of area of the piston n over

the piston l' , or, in other words, is equal in area to the bore of the cylinder A . When, therefore, the water is allowed to flow from the pipe f , it relieves the pressure against the piston n , and also against that of the piston l , by allowing it to flow out freely through i^2 and i' into f , and thereby permit the pistons to descend, and thus open the supply flowing from the main.

It is obvious from the foregoing that the internal cylinders, h' and b , may be dispensed with and the pistons made to work in the shell or cylinder A by simply separating the induction and educt pipes to the distance of the length of the cylinder h' apart, and that the stem i' may also be made solid by making a port or pipe pass outside of the cylinder A from the bottom of the chamber h into the chamber formed between the pistons l and n .

Having thus described my invention, what I claim as new, and desire to secure by Letters Patent, is—

A pressure-regulator for liquids consisting of the following elements: first, a tubular shell closed at the ends and having lateral induct, educt, and relief openings, the educt being longitudinally between the other two; second, three pistons fitted within such shell, rigidly attached to and moving with a single piston-stem, which penetrates the end of the shell nearest to which is the relief-opening, the first or lowest piston playing below the induct-opening, the second or highest piston playing above the educt and to and beyond the relief-opening, and the third piston being between the other two, situated and serving as a valve to open and close the induct; third, a conduit or water-way opening into the piston-chamber at one end below the first piston and at the other end between the other two pistons, and which may be either through the piston-stem or in the body of or exterior to the shell; fourth, a weighted lever, or its mechanical equivalent, adjusted against the outer end of the piston-stem, actuating it inward against the water-pressure, all combined and operating substantially as set forth.

PATRICK HARVEY.
